UNITED STATES PATENT OFFICE.

SIDNEY E. KELSEY, OF KANSAS CITY, MISSOURI.

STILL OR RETORT.

1,092,366.

Specification of Letters Patent.

Patented Apr. 7, 1914.

Application filed September 9, 1913. Serial No. 788,792.

To all whom it may concern:

Be it known that I, SIDNEY E. KELSEY, a citizen of the United States, residing at Kansas City, in the county of Jackson and 5 State of Missouri, have invented certain new and useful Improvements in Stills or Retorts; and I do declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 My invention relates to stills or retorts, and more particularly to a device of that character wherein compounds, such as are contained in petroleum and coal distillates, may be distilled, cracked, or broken up into 20 lighter molecules, and from which the resultant products may be drawn; the principal object of the invention being to provide a still or retort wherein the compounds to be acted upon are caused to flow through a 25 more refractory, heated fluid, and over suitable baffles, in order to break their more complex molecules, and vaporize or gasefy the molecules during their travel through the still. In accomplishing this object I 30 provide a still comprising a casing of refractory material containing a mass of less refractory material, such as mercury, lead, zinc, glass, or other element, compound, or mixture, and heat the casing to such a degree 35 that the interior mass is liquid and at a temperature above the boiling point of the most volatile compound to be treated. I then conduct the compound or mixture of compounds to be treated to near the bottom of the mass 40 within the casing and deliver same into the mass, so that it may rise therethrough or mix therewith and some of it be broken up and become vaporized or gasefied during its upward travel; suitable baffles being placed 45 within the casing to retard somewhat the upward flow and to provide additional heating surfaces.

The preferred form of structure embodying the invention is illustrated in the accompanying drawing, to which reference will be made by reference numerals, and wherein a still comprising the improvements is illustrated in vertical section.

Referring more in detail to the drawing:—1 designates a furnace having an upper opening 2 and comprising a burner 3, of

any suitable type. Projected downwardly through the opening 2 to near the bottom of the furnace is a casing or shell 4; the upper portion of which extends above the top 60 of the furnace, and has pipes 6 and 7 opening thereinto at different elevations; the pipe 6 being provided with a check valve 8 and the pipe 7 with a manually controlled valve 9, for the purposes presently set forth. 65

Opening through the top of the casing and mounted on the upper head 11, preferably by means of screw threads 12, is a pipe 13 which extends downwardly to near the lower head 14, so that it may deliver material into the lower portion of the casing, the upper end of the pipe being connected with a suitable pump 15, or other pressure device, and equipped with a check valve 16 to prevent back flow from the casing to the pump. 70

The casing is partially filled, preferably to the level of the top of the furnace, with a refractory mass 17, such as mercury, lead, zinc, or the like, having a fusing point below that of the casing; and contained within said mass, and within the casing above the top of the mass, are baffles 18, preferably consisting of metal turnings, filings, or the like, of a more refractory material than the mass 17, so that they will not fuse therewith, 85 which are so shaped, regularly or irregularly, as to make the ratio of heating surface to volume the largest practicable, and which are preferably loose within the casing. 90

The check valve 8 on the upper pipe 6 comprises a spring 20, which is adapted to yield and allow the valve to unseat when pressure of vapor within the casing is sufficient to overcome the tension of the spring. 95

In using the retort or still, presuming the parts to be constructed and assembled as described, the furnace is operated to heat the casing and the mass of less refractory material and baffles contained therein. The 100 material to be acted upon is then injected through the pipe 13 and delivered into the liquid mass in the bottom of the still. When the material leaves the lower end of the pipe, it ascends through the denser mass 105 and around and between the baffles 18, the more volatile compounds of the material or fluid being vaporized more quickly than the less volatile compounds, so that they rise to the surface more quickly than the latter; 110 some of the molecules of the material being broken into molecules of lighter weight

during the upward travel of the material through the refractory mass. After passing through the refractory mass, vapors and gases of the material pass out through pipe 6, and the residue is drawn off through pipe 7 or both may be drawn off through the same pipe and that portion of the liquid which has not been brought to the proper boiling point may be again passed through 10 the still, or through one or more similar stills which may be heated to higher degrees in order to reduce the heavier molecules.

During the operation of the still or retort, the baffles serve to increase the heating surface within the still, without necessitating contact of the material to be treated with the walls of the lower part of the casing or shell, so that the latter may be heated to a degree which otherwise might be destructive 20 to the material, but which, because of the present arrangement, may be heated to a temperature that will insure the maintenance of the required high temperature of the liquid mass 17 and of the baffles 18. The 25 baffles, and particularly those located above the level of the mass 17, also serve to retard and prevent the escape of the non-volatilized portions of the material being treated with the vapors and gases through the pipe 6.

30 In case the density of the material composing the liquid bath exceeds the density of the material composing the baffles, some of the baffles are forced beneath the surface of the liquid by the weight of the baffles not 35 submerged; but the baffles may be made to

extend downward as far as desired, the buoyant effect of the liquid mass being resisted by the downward pressure of the upper still head.

Having thus described my invention, 40 what I claim as new therein, and desire to secure by Letters Patent, is:—

1. A still or retort comprising a shell having an outlet port in its upper portion, a mass of refractory material in fluid state 45 contained within the lower portion of the shell, means for conducting material to be treated into said mass, and floating baffles contained within the shell and immersed in said mass.

2. A still or retort comprising a shell, a mass of refractory material in fluid state 50 partially filling said shell, baffles contained within the shell, within and above said mass, means for conducting material to be treated into said mass, and exhaust pipes communicating with the interior of said shell at different elevations.

3. A still or retort comprising a shell having an outlet port, a mass of refractory material in fluid state contained within the lower portion of the shell, baffles contained within the shell, and means for conducting material to be treated into said mass.

In testimony whereof I affix my signature 60 in presence of two witnesses.

SIDNEY E. KELSEY.
